UNITED STATES PATENT OFFICE.

RUDOLPH CONRADER, OF ERIE, PENNSYLVANIA.

CONTROLLING MECHANISM FOR COMPRESSORS.

Application filed December 3, 1923, Serial No. 678,369. Renewed May 11, 1928.

The invention is designed to control compressors, particularly electrical motor driven compressors maintaining a uniform pressure in a receiver and starting and stopping the motor in accordance with the pressure requirements. With such devices it is desirable to start the motor with the compressor running light and to load up the compressor after the motor is in motion and one of the purposes of the invention is to accomplish this under the varying conditions that may arise in the operation. Features of various parts of the mechanism which form the subject matter of the invention will appear from the specification and claims.

The invention is illustrated in the accompanying drawings as follows:—

Fig. 1 shows a central vertical section of a discharge unloader forming part of the apparatus.

Fig. 2 a similar view, the view being at right angles to that of Fig. 1.

Fig. 3 a central vertical section of a regulating device.

Fig. 4 a section on the line 4—4 in Fig. 3.

Fig. 5 a central section of a part of the switch mechanism and part of the controlling mechanism, particularly the retarding device.

Fig. 6 a section on the line 6—6 in Fig. 5.

Fig. 7 a section on the line 7—7 in Fig. 5.

Fig. 8 a side elevation of the safety device shown in section in Fig. 5, the view being at right angles to that of Fig. 5.

Fig. 9 a side elevation of the assembled mechanism.

Fig. 10 a sectional view of valve controlling water circulation to the pump jacket.

1 marks the electric motor, 2 the drive pulley of the motor, 3 a belt extending from the drive pulley to the driving pulley 4 of the compressor 5. These parts may be of ordinary construction. The compressor discharges through a pipe 6 to a receiver 7. An unloader is arranged in the pipe 6, the unloader having a body 8 with a diaphragm 9. A valve seat 10 is arranged in the diaphragm and a check valve 11 operates on this seat. The check valve is held to its seat by a spring 12. It has a plunger 13 which operates in a cylinder 14, the effect of which is to allow the check valve to gradually open and stay open during the ordinary pulsations of the compressor, the leakage past the plunger permitting the closing of the valve when the pump stops. The cylinder has a cap 14^a which when removed gives access to the seat 10. An un-

loader valve seat 15 is arranged in axial alignment with the seat 10 and is sufficiently smaller than the seat 10 to be assembled through the cylinder and the opening for the seat 10. An unloader valve 16 operates on the seat. It has a stem 17 extending through a spider 18. A spring 19 is arranged around the stem and operates against a shoulder 20 at the end of the stem. A piston 21 operates against the stem, this piston operating in a cylinder 22. The cylinder is screwed into a screw-threaded socket 23 extending from the body 8. A gasket 24 is arranged in the bottom of the socket making a tight joint as the cylinder is screwed to place. The gasket extends inwardly from the wall of the cylinder and forms a seat for the piston 21 at the extreme of its movement, thus making a tight joint for the piston even though there may be leakage around the walls of the piston. By making the stem separate from the piston the unloader valve may be put in place and the spring adjusted prior to the assembling of the cylinder. A pipe 25 extends from the cylinder to a regulating mechanism in communication with the receiver.

The regulator is formed with a body 26 having an inlet fitting 27 communicating by a pipe 27^a with the receiver. The inlet fitting 27 leads to a cylinder 28 having two sets of radial ports 29 and 29^a discharging to a discharge cavity 29^b. A piston 30 operates in the cylinder over the ports 29—29^a. When the receiver pressure rises to the maximum the piston is moved uncovering the ports 29 and connecting the receiver with the unloader so as to unload the compressor. The same movement closes the exhaust ports 29^a. As the piston returns the ports 29 are closed and the exhaust port 29^a opened permitting the air from the unloader to escape through the front end of the cylinder. A push pin 31 extends from the piston to a swinging arm 32. This arm is pivoted at 33 on the body and has projections 34 in which a screw 35 is mounted. A cross head 36 is mounted on the screw and is adjustable by the screw. Springs 37 extend from the cross head to projections 38 on the body. The angle of the spring to a radial line running from the cross head to the axis of the arm is so arranged with relation to the length of the spring as to give a decreasing leverage to the spring with the shortening of the arm equal to the increase in strength of the spring so that with a starting movement of the piston the

piston moves to the end of its stroke and the same condition exists with each point of adjustment of the cross head. In order to prevent frequent reversals of the pressure device the arm 32 is provided with cam surfaces 39 and 39^a which are operated upon by cam surfaces 40 and 40^a of a lever 41. The lever 41 is pivoted at 42 on the body. A stud 43 extends through an opening 44 in the lever and a spring 45 is arranged on the stud and adjusted by a nut 46. The force of this lever opposes the initial movement of the arm 32 in both directions but ceases resistance before the piston reaches the ports so that there is an immediate reversal with the uncovering of either port. This specific regulating device forms the subject matter of a companion application of even date herewith.

20 The air is discharged from the regulating device through an outlet fitting 47 connected by a pipe 48 with a retarding storage chamber 49, the retarding storage chamber being connected by the pipe 25 with the unloader. 25 The operation of this will be more fully described later. The switch mechanism is controlled by the regulator. A pipe 49^a extends from the discharge chamber 29^a—29^b of the regulator to a cylinder 50. The cylinder 50 is mounted on a base 51, the base forming a mounting for the storage chamber 49. The base has a socket 52 in which is arranged a gasket 53. The cylinder is drawn into the socket against the gasket by screws 54. A 35 piston 55 is mounted in the cylinder and at the extreme of its movement seats on the gasket thus preventing a leakage between the walls of the piston and the cylinder. The piston is normally forced upwardly by a 40 spring 56. A stem 57 extends through the top of the cylinder to a switch block 58 of insulating material. Two plates 59 are mounted on the switch block 58 and these are in position to be contacted by contact posts 60, there being two of the posts 60 connected with the line wire 61 and two of the posts 60 connected with the wire 62 extending from the switch to the motor so that with the closing of the two plates 59 on the posts 60 the two sides of 45 the motor are connected with the two sides of the line wire. When the pressure in the receiver rises to a point to move the piston so as to turn the air or fluid pressure into the discharge passage 29^b the pressure on the piston 55 opens the switch 58 and retains it open so long as the receiver pressure is such as to retain the piston in position to open the ports 29. When the ports are closed the pressure from the cylinder 50 is exhausted through 50 the ports 29^a and the spring 56 operating on the piston closes the switch.

55 It will be understood that the same regulating action of the piston which exhausts the air from the cylinder 50 and thus closes the switch also exhausts the air from the un-

loader so as to operate the unloader to start pumping. It is desirable to retard the pumping until the motor gets under way and in order to accomplish this the check valve 63 operates on a seat 64 and controls the connection between the discharge fitting 47 and chamber 29^b. This is held to its seat normally by a light spring 63^a and has a slight opening 64^a through which the air from the unloader and the retarding storage chamber may escape. As soon as there is a sufficient escape of air from the unloader the unloader loads up the compressor. The time as to the loading of the compressor may be controlled by the size of the escape opening 64^a with relation to the air trapped in the retarding storage chamber and the unloader. Thus more time may be given by increasing the size of the chamber or by decreasing the size of the passage 64^a. When the compressor unloads, however, the valve 63 is instantly opened so that the unloader operates at the same time that the motor is stopped.

50 It is desirable to provide a means whereby the compressor will be unloaded whenever there is a stoppage of the motor through a break in the line, or for other causes than the direct control of the regulator and this is accomplished in the present device by the following mechanism:—A valve body 65 is connected by a pipe 66 with the retarding chamber 49. A valve opening 67 controls the passage of the pipe 66 and a needle valve 68 controls the opening. The needle valve has a stem 69 extending to a yoke 70. A spring 71 operates against the yoke and tends to open the needle valve. The lower end of the yoke is connected with the core 71^a of a solenoid 72 and the solenoid is connected by a shunt line 73 with the line 62. A pipe 74 connects the valve body with the pipe 27^a and thus with the receiver. When, therefore, there is a break in the line and consequently there is a cessation of current in the solenoid the spring 71 opens the valve 67 and permits receiver pressure to pass into the retarding chamber and thence to the unloading valve and thus the compressor is maintained in an unloaded condition so that if the line is closed the compressor will be in position to start again. As soon as the current is turned on the solenoid will close the valve 67 and permit the compressor to operate under the control of the regulator.

55 It is desirable to provide the pump with a cooling system in the form of a water jacket and it is desirable to cut off the circulation of water through this jacket during the periods when the pump is stopped. This is accomplished in the present device by the following mechanism: A water jacket 75 is arranged on the pump cylinder. This is connected with a source of water supply through a pipe 76. A valve 77 controls the flow of water to the jacket. A valve head 78 is arranged in the

valve and carried by a stem 79. The stem 79 is secured to a diaphragm 80. The diaphragm is clamped on the body by a cap 81 forming a diaphragm chamber 82. A pipe 49^b extends from the pipe 49^a to the diaphragm chamber 82. When, therefore, the receiver pressure reaches the desired maximum and air is turned into the discharge passage 29^b it communicates by way of the pipe 49^a and pipe 49^b to the diaphragm chamber closing the valve at the same time that the mechanism hereinbefore described stops the motor and unloads the compressor. As soon as the piston 30 uncovers the port 29^a 15 on the reduction of pressure the air is exhausted through these ports and relieves the pressure on the diaphragm thus permitting the valve 78 to open so that while the pump is in motion the water circulation may continue.

20 What I claim as new is:—

1. In a controlling mechanism for compressors, the combination of a compressor; an electric motor driving the compressor; an unloader for the compressor; an electric line supplying current to the motor; a regulator sensitive to pumped fluid controlling the unloader; and means acting independently of the regulator for actuating the unloader with a stoppage of the current in the line connected with the electric motor.
2. In a controlling mechanism for compressors, the combination of a compressor; an electric motor driving the compressor; a line supplying current to the motor; a switch 25 controlling the line; a fluid actuated device controlling the switch; an unloader for the compressor; a regulator controlling the unloader and fluid actuated device; and a device controlling the unloader independently of the regulator actuated to unload the compressor with the stoppage of current in the line.

3. In a controlling mechanism for compressors, the combination of a compressor; an electric motor driving the compressor; a line supplying current to the motor; a switch controlling the line; a fluid actuated device controlling the switch; an unloader for the compressor; a regulator controlling the unloader and the fluid actuated device, said regulator being sensitive to pumped fluid; means for retarding the movement of the unloader to loaded position after the movement of the regulator to close the switch; and means acting independently of the regulator for unloading the compressor with the stoppage of current in the line.

4. In a controlling mechanism for compressors, the combination of a compressor; an electric motor driving the compressor; an unloader for the compressor; an electric line supplying current to the motor; a regulator sensitive to pumped fluid controlling the unloader; means acting independently of the regulator for actuating the unloader

with the stoppage of current in the line connected with the electric motor comprising a connection leading to a source of pressure; a valve controlling said connection; and an electrically actuated device in the line controlling the valve. 70

5. In a controlling mechanism for compressors, the combination of an unloader comprising an unloader valve; a stem extending from the valve; a spring tensioning the valve secured on the stem; a cylinder arranged over the valve stem; and a piston in the cylinder adapted to be assembled independently of the stem for acting on the valve. 75

6. In a controlling mechanism for compressors, the combination of an unloader comprising an unloader valve; a stem extending from the valve; a valve body having a socket therein; a cylinder seated in the socket; and a piston operating in the cylinder against 80 the valve stem adapted to seat in the socket.

7. In a controlling mechanism for compressors, the combination of a controlling device for the compressor comprising a body having a socket; a gasket in the socket; a cylinder seated on the gasket; a piston operating in the cylinder and seating at its extreme movement on the gasket; a connection leading to the cylinder from a source of pumped fluid supply; and controlling devices actuated by the piston. 90

8. In a controlling mechanism for compressors, the combination of a regulator sensitive to pump pressure; an unloader controlled by the regulator; an electric motor driving the compressor; a switch controlling the electric motor; a pressure actuated device controlled by the regulator controlling the switch; and a retarding device interposed between the regulator and the unloader retarding the movement of the unloader to load position comprising a retarding storage chamber in the connection between the unloader and regulator, and a restricted leak from the chamber, said restricted leak discharging 100 through the regulator and being closed by the regulator with the unloader in unloaded position. 105

9. In a controlling mechanism for compressors, the combination of a compressor; an electric motor driving the compressor; an electric switch controlling the motor; a fluid actuated device controlling the switch; an unloader acting on the compressor; and a regulator sensitive to pumped fluid and acting on the pressure actuated device and unloader simultaneously to open the switch and unload the compressor acting in sequence through a pneumatic device to close the switch and load the compressor, said pneumatic device comprising a retarding means for the unloader having a leak, said leak discharging 110 to the regulator and being closed with the unloader and unloaded position. 120

10. In a pressure controlling device, the 125

combination of a regulator sensitive to pressure and controlling a supply and exhaust of fluid under pressure; an unloader; and a connection between the regulator and unloader comprising a retarding device having a leak from the unloader closed by the regulator with the unloader in unloaded position.

11. In a controlling mechanism for compressors, the combination of an electric motor; a switch controlling the electric motor; a regulator sensitive to pressure; and a pressure device controlling the switch controlled by the regulator and comprising a cylinder, a piston in the cylinder, and a seat on which the piston closes when holding the switch in open position.

12. In a controlling mechanism for compressors, the combination of a compressor; an electric motor driving the compressor;

an unloader for the compressor; an electric line supplying current to the motor; a regulator sensitive to pumped fluid controlling the unloader; means acting independently of the regulator for actuating the unloader with an opening of the line connected with the electric motor comprising a connection leading to a source of pressure; a valve controlling said connection; an electrically actuated device in the line controlling the valve; and a retarding device retarding the moving of the unloader to loaded position, said retarding device acting on the unloader when brought to unloaded position by either the regulator or means.

In testimony whereof I have hereunto set my hand.

RUDOLPH CONRADER.
